UNITED STATES PATENT OFFICE.

CLINTON W. BEDELL, OF NEW YORK, N. Y.

INDICATING DEVICE.

1,131,314.

Specification of Letters Patent. Patented Mar. 9, 1915.

Application filed February 24, 1913. Serial No. 750,093.

To all whom it may concern:

Be it known that I, CLINTON W. BEDELL, a citizen of the United States, residing at New York, in the county and State of New York, have invented certain new and useful Improvements in Indicating Devices, of which the following is a full, clear, and exact description.

This invention relates generally to indicating devices wherein it is desired to instantly determine or find any desired sum or figure.

The object of the present invention is to provide an economical, simple and compact indicator, which by its construction and the arrangement of its parts may be adapted to various uses, wherein it is desirable or expedient to use means to quickly or rapidly compute or indicate the sum of a plurality of known figures or amounts.

A further object of my invention is the production of a device of the character above set forth, which, while adaptable to various uses, is especially applicable to the requirements of those making use of the "parcels post system" and is arranged and intended to instantly and correctly indicate the various rates of postage on packages of different weights to be mailed to destinations within the several zones adopted and promulgated by the Post Office Department in carrying the parcels post system into effect.

Briefly stated, my invention comprises a plurality of plates of any convenient configuration or contour, between which are mounted a series of rotatable disks bearing indicating figures, which are adapted to cooperate with certain indicating mediums on said plates in the manner as will be hereinafter fully set forth.

I will now describe my invention with reference to the accompanying drawings, then point out with more particularity the essential element of novelty therein in the appended claims.

In the drawings: Figure 1 is a plan view of my improved indicator showing what I prefer to term the top plate, a portion thereof being removed to display one of the indicating disks; Fig. 2 is a similar view of the opposed or bottom plate having a portion cut away to disclose the reverse side of the disk shown in Fig. 1, Fig. 3 is a view of

one side of my device as shown in Figs. 1 55 and 2, Fig. 4 is a section of the device shown in Fig. 1 illustrating a modified form thereof, wherein the reading or sight openings are of a different type than those shown in Fig. 1, and Fig. 5 is a view of the reverse 60 side of the structure shown in Fig. 4, its relation thereto being similar to the relation of Fig. 2 to Fig. 1.

Referring now to the drawings in detail, in which like characters of reference are 65 employed to designate similar parts throughout the several views, 7 is a plate of any convenient size, preferably of rectangular configuration, as shown, but which may be provided with rounded corners and 70 which may be made of card board, celluloid, aluminum or any other material suitable for the purpose. A second plate 8, of the same configuration and preferably of the same material as plate 7, is provided, one of the 75 plates 7 and 8 being adapted to form the top member of my device and the other the bottom or base member. Located on the opposite parallel edges 10 and 11 of each of the plates 7 and 8 are a plurality of slots 80 or sight openings 12, preferably of the configuration illustrated and arranged as shown in Figs. 1 and 2.

For the sake of clearness and convenience of description, I will hereinafter refer to 85 the plate 7 as the top plate of my device, it being understood that the arrangement of the slots or sight openings 12 in each plate is the same so that when the device is assembled the slots on one plate are positioned directly opposite the corresponding slots of the other plate.

Pivotedly mounted between the plates 7 and 8 are a plurality of rotatable disks 13, the pins or other suitable pivots 14 passing 95 through the plate 7 and 8 thereby serving to secure all of the parts of my device in assembled and co-operative relation. It will be noted that the disks 13 are so disposed between the plates with relation to the slots 100 or openings 12 that the portions of both surfaces of each disk contiguous to the slots 12 in the plates 7 and 8, adjacent to which each disk is positioned, are disclosed to view simultaneously, the peripheries 16 of the respective disks protruding slightly beyond the outer edges of the slots to provide a surface on which a sufficient purchase may be

obtained to rotate the disks for the purposes hereinafter set forth.

As will be apparent from the drawings, the outer surface of each plate 7 and 8 may be embellished with any suitable or desired indicia or the like in connection with which my invention may be adaptable. In the present embodiment of any invention, the top plate 7 has printed upon its outer surfaces 10 face a "zone table" 17 used in connection with the "parcels post" system. Adjacent and preferably below each slot or opening 12 on the top plate are arranged the letters "lbs" denoting pounds, the particular zone 15 for which the respective disks are to be used being suitably indicated on the surface of the plate directly over each disk.

The surface of each disk 13, as will be manifest from the drawings, contiguous to 20 the underside of the top plate 7 is provided with suitable numerals 18 to indicate the fixed or specified weights of parcels or packages which may be mailed under the "parcels post" rules, each numeral being located 25 adjacent to the periphery of its disk, so that when the rate of postage on a package of a certain known weight within a specified zone is to be determined, the disk of that particular zone is rotated until the proper 30 weight numeral appears within the slot for that disk. This operation simultaneously causes the exact amount of postage to be affixed to the package, to be displayed within the corresponding or "cents" slot 12 of 35 that disk in the bottom or under plate 8, the arbitrary rate of postage 19 for that weight and zone being printed or otherwise indicated on the surface of the disk 13 adjacent to the innerside of the plate 8, and directly 40 in line with the weight numeral on the opposite surface of the disk.

As an example of the operation of my device, to determine the rate of postage on a package weighing five pounds, to be carried within zone 4, the disk for that zone 45 will be rotated until the figure 5 appears within the "lbs." slot as shown in Fig. 1. By this operation the correct postage rate thirty-two cents for five pounds within zone 50 four is displayed within the slot on the bottom plate (see Fig. 2) so that the postage rate may be instantly found by the simple expedient of reversing or turning over the device.

55 In the modification of my invention shown in Figs. 4 and 5, in lieu of the slots 12, I have provided the circular sight openings 20 preferably arranged as shown, these openings 20, having the same function as 60 the slots 12 shown in Figs. 1 to 3 and being similarly oppositely disposed with relation to each other, the arrangement of the plates 7 and 8 and the method of operation and arrangement of the disks 13 being the same 65 as in the preferred form of my device.

While I have shown and described my invention with reference to a particular embodiment thereof, it is obvious that it is applicable to many other forms of use and that the structure may be varied in minor details without departing from the spirit and scope of my invention.

Having thus described my invention what I claim as new and desire to secure by Letters Patent is:

1. In a calculating device, the combination of a pair of superposed plates, one of said plates being provided with weight indicating characters, the other of said plates having indicia for indicating coin denominations, and a plurality of disks interposed between said plates, the surfaces of each disk having numerals thereon of different values relative to said weight characters and said coin indicia and means whereby said disks may be rotated to bring a specified numeral in register with a weight indicia and simultaneously bring a numeral on the opposite side of the disk into register with a coin indicia, for the purposes specified.

2. In a device for indicating postage rates on parcels within specified zones of a parcels post system, the combination of a pair of plates having a plurality of rotatable disks interposed therebetween, one disk being provided for each zone in the system, each of said disks having on one surface thereof a series of figures indicating weight, the opposite surface of each disk bearing postage rates as specified for each zone, the prescribed rate for a specific weight of parcel and such weight indicia on the opposite surfaces of each disk being in alignment, and oppositely positioned elongated slots located in each plate in proximity to each of said disks and merging into the edges of said plates, whereby upon the rotation of a particular disk to bring a certain weight indicia within the adjacent slot, the postage rate for such weight in the particular zone for which the operated disk is provided, will simultaneously appear within the slot in the opposite plate.

3. A calculating device consisting of a pair of superposed plates, the surface of one of said plates bearing a distance table sub-divided into zones, said plate being sectioned numerically to correspond with each zone and having weight indicia within each of said sections, the other of said plates being sectioned correspondingly to said zone sections of said first-named plate and provided with coin denomination indicia within each section, and a plurality of disks interposed between said plates and having on their opposite surfaces numerals of different value, and means whereby said disks may be rotated to bring a specified numeral into register with a specified zone section on said first plate to show a given weight

and thereby simultaneously effect the registration of a numeral on the opposite side of said disk with the coin indicia on said second plate within the zone section corresponding to that on the first plate, to indicate a relative coin value of a specified weight within such zone

In testimony whereof I have hereunto set my hand in the presence of two subscribing witnesses.
